DESIGN FOR SCISSORS

Charles R. Storz, St. Louis, Mo.

Application January 3, 1944, Serial No. 112,163

Term of patent 7 years

To all whom it may concern:

Be it known that I, Charles R. Storz, a citizen of the United States, residing at St. Louis, Missouri, have invented a new, original, and ornamental Design for Scissors, of which the following is a specification, reference being had to the accompanying drawing, forming part thereof.

Figure 1 is a top view of the scissors when closed.

Figure 2 is a top view of the scissors when open.

Figure 3 is a side view of the scissors.

Figure 4 is a longitudinal vertical sectional view taken on the line 4—4 of Figure 2.

Figure 5 is in part an end view of the scissors and in part a vertical section taken on the line 5—5 of Figure 2.

Figure 6 is a detail section taken on the line 6—6 of Figure 1.

What is claimed is:

An ornamental design for a pair of scissors, as shown.

CHARLES R. STORZ.
